WILLIAM HAINSWORTH WATSON, OF BRADFORD, ENGLAND

TWISTING MACHINE

Application filed December 24, 1931, Serial No. 583,065, and in Great Britain April 21, 1931.

This invention relates to twisting machines either of the cap, ring, or flyer type, of the kind having spindles both before and after the feed rollers, the invention having for its principal object to meet the present day demand for machines giving increased production and at the same time a better quality of work.

It is a comparatively easy matter to increase production at the expense of the quality of the product, while it is equally easy to improve the product at the expense of the output, but to achieve both is extremely difficult.

Specifically, the invention aims, primarily, to secure materially higher spindle speeds than have been possible hitherto, secondly, to increase considerably the number of turns put into the yarn, thirdly, to secure greater accuracy in the twist imparted to the yarn than is obtainable by machines now in use, fourthly, to reduce the number of operations performed by an operative after a stoppage, and fifthly, to eliminate the personal equation when wrapping the yarns on the feed rollers and also when setting the machine in motion.

Former proposals to increase the output of a machine by putting twist into the yarn both before and after the feed rollers, have not taken into account or have not provided for all the factors essential to the achievement of the results contemplated by this invention.

It has been found that to secure absolute uniformity in the twist necessitates obtaining a more positive hold on the yarn between the two rows of spindles and also better driving adhesion between the feed rollers and the yarn than is possible by merely nipping the yarn frictionally between the feed rollers, and the yarn must be set up when the feed rollers and spindles of the appropriate spindle unit are stationary.

With the present invention, therefore, these desiderata which are essential to an improvement in the quality of the product are combined with those factors which make for increased output; advantage being taken of the known arrangement of open-ended

feed rollers in order to facilitate wrapping on, these rollers being positively driven and disconnectible from their driving means, and also of the known method of braking the spindles to arrest them simultaneously with the stoppage of the feed rollers.

According to the invention a twisting machine of the kind referred to is provided with open-ended feed rollers whereof the lower feed rollers are each positively driven and disconnectible from its driving means and each cooperates positively with the yarn which is wrapped completely therearound in addition to being nipped between the upper and lower feed rollers, each upper feed roller is also provided with means for elevating it bodily co-acting with means for disconnecting simultaneously the corresponding lower feed roller from its drive and arresting said roller, and interconnected braking means actuated by the elevation of each upper feed roller are provided for stopping the spindles appropriate thereto simultaneously with the elevation of the upper feed roller and with the disconnection of the lower feed roller, in order to enable the yarn to be set up after a breakage or when starting up.

Means are provided for maintaining each of the upper feed rollers positively in an elevated position while the thread is being wrapped once or twice around the corresponding lower feed roller; and upon the lowering of an upper feed roller, after the thread has been wrapped on the corresponding lower feed roller, the re-engagement of said lower feed roller with its driving means and the re-starting of the spindles occurs simultaneously with the establishment of frictional driving contact between the upper feed roller and the thread wrapped on the lower feed roller.

The feed rollers may be mounted so as to rotate either normal to or at an angle to the vertical plane of the machine, or they may be parallel to the line of the machine.

The invention is illustrated by way of example in the accompanying drawing in which many parts are omitted which are not essential to the understanding of the inven-

tion, Figure 1 being a sectional elevation of a spindle unit, and Figure 2 being a detail view to show the path of the thread.

Referring to Figure 1 of the drawing, the 5 back spindles 1 and front or lower spindles 2 are supported respectively by the spindle rails 3 and 4 and on said back spindles are bobbins such as 5 and on the front spindles bobbins such as 6; the whorl 7 of each back 10 spindle being formed with a braking flange 8 and the whorl 9 of each front spindle with a similar flange 10.

11 is a continuous beam extending for the length of the machine upon which beam there 15 are bolted a series of flanged castings 12, one opposite each pair of back and front spindles, whereof each casting is integral at bottom with a tubular housing or bearing 13 in which is received the forwardly extending arbor 14 20 of a lower feed roller 15, said arbor 14 being slideable axially in said bearing 13 and also axially through a driving pinion or worm 16 between which and a collar 17 secured at the inner end of said arbor there is confined 25 a coiled return spring 18. The pinion or worm 16 meshes with a gear or worm wheel 19 carried by a driving shaft 20 wherefrom the lower feed rollers 15 receive their rotary motion. Any other suitable type of gearing 30 may of course be employed if desired.

The worm 16 is integral with, or may be secured upon, a sleeve 21 which has also secured to it, or is integral with, one member 22 of a serrated or toothed clutch which abuts 35 against a facing 23 formed on the rear end of the housing or bearing 13, the other member 24 of said clutch being of smaller diameter than the member 22 and being accommodated within a recess 25 in the housing 13, 40 said clutch member 24 being pinned or otherwise suitably secured to the arbor 14.

Each upper feed roller 26 is mounted upon an arbor 27 secured to or integral with the 45 forwardly projecting arm 28 of a bell-crank lever articulated at 29 to the head of a stem 30 projecting upwardly from the lower feed roller arbor bearing 13, the other or upwardly projecting arm 31 of said bell-crank lever forming a hand lever.

The arm 31 of each bell-crank lever is fitted with a trigger lever 32 fulcrumed thereto at 33 and cranked or off-set at its upper end so as to be in alignment with the arm or hand 50 lever 31, said trigger lever 32 being formed with a right-angled toe piece 34 adapted to be engaged with a lug 35 integral with a fixed collar 36 located on the pivotal axis or stud 29 of the bell-crank lever. A spring 37 tends 55 to urge the trigger lever 32 away from the hand piece 31.

Against the flange 8 on each spindle 1 is adapted to press (in known manner) the pad 38 of a frictional brake lever 39 from which 60 there extends upwardly a spring blade 40

with which an adjustable stop 41 is designed to engage in order to apply the brake to the spindle, as will be explained hereafter, and the similar flange 10 on each lower or front spindle 2 is engaged by a similar pad 42 on a frictional brake lever 43 each of which latter levers 43 is connected by means of a rod 44 to a boss 45 on the corresponding arm 28 supporting the upper feed roller 26, a spring 46 being confined between each brake lever 43 and a washer 47 and locknuts 48, 48, screwed on to the lower end of the rod 44, whereby adjustment of the spindle braking means can be effected.

Each of the aforesaid adjustable stops 41 takes into a lug 49 formed on a right-angled arm 50 pivoted at 51 to a rearward extension 52 of the stem 30, the upper member of the arm 50 being located in the path of movement of a stud or pin 53 carried by a rearward extension 54 of the arm 28 of the bell-crank lever.

In rear of each lower feed roller 15 there is arranged an arm 55 pivoted at 56 to housing 13 and having a curved abutment face 57 90 contacting with the back of the roller 15, said arm 55 extending upwardly, parallel with and close to the arm 28 of the bell-crank lever and terminating in a slightly curved end 58 against the underside of which bears a stud 95 or pin 59 fixed to the arm 28.

It will be apparent that when handle 31 and trigger lever 32 are grasped and moved angularly backwards (as shown by dotted lines in Figure 1) to elevate an upper feed 100 roller 26, the stop or pin 59 on arm 28 will cause the upper end 58 of arm 55 to move forwards and thereby to press the abutment face 57 against the lower feed roller 15 which, together with the arbor 14 will be moved axially 105 forwards and disengage clutch members 22, 24, the pressure and friction on the rear face of the lower feed roller 15 being sufficient to stop rotation of the roller.

In Figure 2 the path of the yarn or thread 110 is seen at A. From each bobbin 5 the thread passes over traverse guides such as 60 thence under each upper feed roller 26 over traverse guides such as 61, being also wrapped round each lower feed roller 15 (when stopped as just described), and thence through guides such as 62 to bobbins 6.

Upon the lowering of an upper feed roller 26, after the thread has been wrapped on the corresponding lower feed roller 15, the re-engagement of said lower feed roller with the clutch member 22 and driving means 16, 19, 20, occurs simultaneously with the establishment of frictional driving contact between the upper feed roller 26 and the thread 125 wrapped on the lower feed roller 15. Similarly, the co-operation between the elevating means for the upper feed rollers, the means for arresting the lower feed rollers, and the means for arresting the spindles is such that 130

when an upper roller is lowered, the spindles are caused to commence rotating coincidently with the commencement of rotation of the lower feed roller concerned.

5. All the elements, therefore, of each spindle unit commence to rotate simultaneously when being set in motion, or are arrested simultaneously when wrapping on is necessary.

10. Instead of projecting forwardly at right angles to the vertical plane of the machine, as shown, the arbors supporting the feed rollers 15 and 26 may extend at any other convenient angle, or they may be parallel to the line of the machine.

What I claim is:—

1. A twisting machine for yarns and the like, including spindles carrying bobbins and also including upper and lower feed rollers co-operating with said spindles to feed said yarns and the like to said bobbins, characterized by a series of individual upper feed rollers and a co-acting series of individual lower feed rollers, each upper feed roller and each lower feed roller being mounted on an arbor whereof one end is unobstructed by a bearing, means to elevate bodily each upper feed roller, means to maintain in each upper feed roller positively in an elevated position, each lower feed roller being driven positively, and means associated with each upper feed roller to disengage the corresponding lower feed roller from its driving means and arrest said lower feed roller when said upper feed roller is elevated.

2. A twisting machine for yarns and the like, including spindles carrying bobbins and also including upper and lower feed rollers co-operating with said spindles to feed said yarns and the like to said bobbins, characterized by a series of individual upper feed rollers and a co-acting series of individual lower feed rollers, each upper feed roller and each lower feed roller being mounted on an arbor whereof one end is unobstructed by a bearing, means to elevate bodily each upper feed roller, means to maintain each upper feed roller positively in an elevated position, each lower feed roller being driven positively, means associated with each upper feed roller to disengage the corresponding lower feed roller from its driving means and arrest said lower feed roller when said upper feed roller is elevated, and means co-operating with said elevating means and with said spindles to stop a spindle simultaneously with the elevation of the corresponding upper feed roller.

3. A twisting machine for yarns and the like, including spindles carrying bobbins and also including upper and lower feed rollers co-operating with said spindles to feed said yarns and the like to said bobbins, characterized by a series of individual upper feed rollers and a co-acting series of individual lower feed rollers, each upper feed roller and

each lower feed roller being mounted on an arbor whereof one end is unobstructed by a bearing, each arbor extending forwardly of the machine, means to elevate bodily each upper feed roller, means to maintain each upper feed roller positively in an elevated position, each lower feed roller being driven positively, means associated with each upper feed roller to disengage the corresponding lower feed roller from its driving means and arrest said lower feed roller when said upper feed roller is elevated, and means co-operating with said elevating means and with said spindles to stop a spindle simultaneously with the elevation of the corresponding upper feed roller.

4. In a twisting machine for yarns and the like, in combination, rotary spindles carrying bobbins, means for arresting rotation of said spindles, an upper series of feed rollers, a lower series of feed rollers, a beam supporting said feed rollers, each of said rollers being unobstructed by a bearing at one end and being disposed each with its axis at an angle to said beam, driving means for said lower feed rollers, said lower feed rollers having yarn wrapped therearound and being disengageable from said driving means, means for elevating each of said upper feed rollers and for simultaneously disengaging the corresponding lower feed roller from said driving means, and connections between said roller elevating means and said spindle arresting means.

5. In a twisting machine for yarns and the like, in combination, an upper series of feed rollers and a co-acting lower series of feed rollers, a beam supporting said feed rollers, a series of rotary spindles located above both said series of feed rollers, a series of rotary spindles located below both said series of feed rollers, bobbins on said rotary spindles, means for arresting rotation of said spindles, each of said feed rollers being unobstructed by a bearing at one end and each being disposed with its axis at an angle to said beam, driving means for said lower feed rollers, said lower feed rollers being disengageable from said driving means, said yarns being wrapped round said lower feed rollers, means for elevating each of said upper feed rollers and for simultaneously disengaging the corresponding lower feed roller from said driving means, and adjustable connections between said roller elevating means and said spindle arresting means.

6. A twisting machine for yarns and the like, including rotary spindles carrying bobbins, means for braking said spindles, a series of individual upper feed rollers and a co-acting series of individual lower feed rollers, said lower feed rollers being disengageably connected to positive driving means therefor, means to elevate each of said upper feed rollers, adjustable connections between said roller elevating means and said spindle

braking means, all of said feed rollers being open-ended towards the front of the machine, said yarns being wrapped round said lower feed rollers, and means to disengage each of said lower feed rollers from its appropriate driving means and to stop said roller simultaneously with the elevation of the corresponding upper feed roller.

7. A twisting machine for yarns and the like embodying a series of spindle units, each spindle unit comprising, a pair of rotary spindles each carrying a bobbin, braking means for said pair of spindles, an open-ended upper feed roller, and a positively-driven open-ended lower feed roller, one of said spindles being located before said feed rollers and one of said spindles being located after said feed rollers, characterized by means for stopping simultaneously all the elements comprising any spindle unit to enable yarn to be wrapped on the lower feed roller and for re-starting all said elements simultaneously after completion of said wrapping on of the yarn.

8. A twisting machine for yarns and the like embodying a series of spindle units, each spindle unit comprising, a rotary spindle carrying a bobbin, braking means for said spindle, an open-ended upper feed roller, and a positively driven open-ended lower feed roller, the axes of said feed rollers projecting forwardly of the machine, characterized by a lever for elevating said upper feed roller from contact with said lower feed roller, means for stopping simultaneously all the elements comprising any spindle unit to enable yarn to be wrapped on the lower feed roller, means for maintaining said upper feed roller positively in an elevated position during said wrapping on of said yarn, and means for releasing said upper feed roller on completion of said wrapping on of said yarn, the stopping and re-starting of the spindle unit being effected by the manipulation of said lever.

9. A twisting machine for yarns and the like embodying a series of spindle units, each spindle unit comprising, a pair of rotary spindles each carrying a bobbin, braking means for said pair of spindles, an open-ended upper feed roller, and a positively driven open-ended lower feed roller, one of said spindles being located before said feed rollers and one of said spindles being located after said feed rollers, the axes of said feed rollers projecting forwardly of the machine, characterized by a lever for elevating said upper feed roller from contact with said lower feed roller, means for stopping simultaneously all the elements comprising any spindle unit to enable yarn to be wrapped on the lower feed roller, means for maintaining said upper feed roller positively in an elevated position during said wrapping on of said yarn, and means for releasing said upper

feed roller on completion of said wrapping on of said yarn, the stopping and re-starting of the spindle unit being effected by the manipulation of said lever.

In testimony whereof he affixes his signature.
